ATTORNEY.

UNITED STATES PATENT OFFICE.

GEORGE NITZ, OF OMAHA, NEBRASKA, ASSIGNOR TO FRANK DAMATO, OF OMAHA, NEBRASKA.

ADJUSTABLE BRUSH HANDLE.

Application filed June 12, 1923. Serial No. 644,893.

To all whom it may concern:

Be it known that GEORGE NITZ, citizen of the United States, residing at Omaha, in the county of Douglas and State of Nebraska, has invented certain new and useful Improvements in Adjustable Brush Handles, of which the following is a specification, reference being had therein to the accompanying drawings.

10 The invention relates to adjustable brush handles, and has for its object to provide a device of this character particularly adapted for use in connection with relatively long sweeping or dusting brushes, and has for its 15 object to provide an adjustable handle which may be adjusted at various angles in relation to the brush head according to the nature of the work being done, such for instance as brushing walls, floors or ceilings. 20 Also to support the brush handle from spaced brackets spaced a substantial distance from the center of the brush head, thereby allowing proper leverage in especially long brushes, and at the same time obviating the 25 present use of a brush handle which is threaded into the brush head, which easily becomes worn and unscrewed when used in connection with relatively long brush heads where the leverage is great during the 30 brushing operation.

A further object is to provide the brush handle with a right angularly disposed member, the ends of which are provided with toothed discs which cooperate with toothed discs carried by the brush head. The toothed discs when interengaged form 35 means for holding the brush handle at various angles to the brush head.

With the above and other objects in view 40 the invention resides in the combination and arrangement of parts as hereinafter set forth, shown in the drawing, described and claimed, it being understood that changes in the precise embodiment of the invention 45 may be made within the scope of what is claimed without departing from the spirit of the invention.

In the drawing:—

50 Figure 1 is a view in elevation of the brush.

Figure 2 is a side elevation of the brush showing a handle adjusted to the position in the same plane as the brush.

Figure 3 is an enlarged sectional view

through a portion of the brush head and a 55 pair of interengaged toothed discs.

Figure 4 is a view showing one of the toothed discs which is carried by the brush head.

Figure 5 is an end view of the brush handle shaft showing the toothed disc carried thereby.

Referring to the drawing, the numeral 1 designates a brush head of the dust brush type, which is relatively long, and is generally 18 inches in length or longer. In brushes of this character, at the present time, handles are threaded or screwed into a threaded aperture of the brush head centrally thereof. It has been found that where 70 conventional forms of handles are used, on account of the great length of the brush, the brush easily becomes loose or unscrewed or the threads become stripped during use. It has also been found that brushes of this 75 character are used for sweeping floors, walls and ceilings and a handle secured to the brush at a fixed angle renders some of its operations, especially the overhead ones, difficult. To obviate the above difficulties the 80 handle member 2 is adjustably connected to the brush head 1 in a manner whereby it may be adjusted to various angles in relation to the brush head as shown in dotted lines in Figure 2. It will be seen that by 85 adjusting the handle 2 to various angles, the handle may be adjusted according to the nature of the sweeping or brushing operation.

The lower end 3 of the handle 2 is provided with a right angularly disposed shaft 4, to which the handle 2 is secured substantially centrally of the shaft 4. The shaft 4 is relatively long and adjacent its outer ends is provided with discs 5, the outer faces of 95 which are provided with radially disposed teeth 6, which teeth engage radially disposed teeth 7 carried by discs 8, and through apertures 9 of which discs 8, the ends of the shaft 4 extend. Threaded on the outer ends of 100 the shaft 4 are nuts 10, which nuts, when tightened securely lock the interengaged discs 5 and 8 together, thereby locking the handle 2 positively at any angle to which it may have been adjusted. When the nuts 10 105 are loosened, the handle 2 may be adjusted to various angles in relation to the brush head 1 by grasping the brush head 1 and

handle 2 and moving the same to the proper position in relation to each other. The teeth 7 and 6 are relatively small and the shanks 11 of the discs 8 have sufficient spring action 5 to allow the teeth to cam past each other. The shanks 11 of the discs 8 are provided with flanges 12 which engage the upper side of the brush head 1 and extend through the brush head 1 and are provided with nuts 13 10 whereby the discs 8 may be securely attached to the brush head. It will be seen that the discs 8 and 5 are located substantial distances from the center of the brush head and consequently the leverage during a sweeping 15 operation is reduced to a minimum, thereby facilitating the sweeping operation.

From the above it will be seen that an adjustable brush handle is provided for use in connection with relatively long brushes, 20 which may be easily and quickly adjusted to various angles in relation to the brush head, and the handle is positively attached to the brush head thereby obviating the

present difficulty experienced where brush handles are threaded into the brush head. 25

The invention having been set forth what is claimed as new and useful is:—

The combination with a relatively long brush head, of an adjustable handle carried thereby, said handle being secured centrally 30 to a transversely disposed shaft, integral toothed discs carried by said shaft, toothed discs carried by the brush head at points spaced from its center, and through which discs the ends of the shaft extend, said 35 toothed discs cooperating to hold the handle at various angles in relation to the brush head and nuts threaded on the outer ends of the shaft and flexible shafts connecting the brush carried discs to the brush, whereby 40 during a handle adjusting operation the brush carried discs will spring outwardly in opposite directions.

In testimony whereof I hereunto affix my signature.

GEORGE NITZ.
